ABSTRACT

An elevator control apparatus comprising a synchronizer movable at a reduced speed proportional to the running speed of an elevator car, an advancer arranged for advancing movement on the synchronizer within a predetermined range for detecting a floor originating a call, and means for determining the running speed of the elevator car depending on the position of the advancer, hence the position of the floor originating the call, relative to the position of the synchronizer, hence the floor position of the elevator car, when the advancer moves and stops at the position corresponding to the floor from which the call is originated. In the elevator control apparatus, a pre-advancer is additionally provided for making advancing movement within a range outside the movable range of the advancer for detecting another floor originating another call so that it can detect calls originating from the range which is outside the detectable range of the advancer.

ELEVATOR CONTROL APPARATUS

This invention relates to an elevator control apparatus and more particularly to improvements in a control apparatus of the kind which determines the running speed and controls the deceleration of an elevator car for moving same toward a floor from which a call is originated.

Such a control apparatus is commonly called a floor controller or floor selector and is presently employed in all kinds of elevator systems. Broadly speaking, the floor controller possesses three functions. It is the first function of the floor controller to detect a nearest serviceable call for an elevator car resting at one of the floors and to determine the running speed suitable for the service. It is the second function of the floor controller to deliver decelerating instructions and apply such instructions to an elevator car moving toward a floor in response to a call originated therefrom so that such elevator car can stop at the target floor. The third function includes display of the position of an elevator car, previous notification of the arriving floor and various other signal display controls.

In order that the floor controller can possess such functions, the floor controller is generally installed in the machinery room above the shaft and comprises essentially a synchronizer which makes vertical movement in synchronism with the movement of an elevator car and whose moving speed is reduced to about one one-hundredth of the running speed of the elevator car by a reduction gear unit, and an advancer which is advanced relative to the synchronizer in response to a call. The advancer is advanced to a position corresponding to a floor from which a call is originated, and upon arrival at such position, an engaging member is actuated to engage a stopper fixed to the frame of the floor controller for stopping the advancer at such position. Then, the elevator car, hence the synchronizer following the movement of the advancer catches up with the advancer. In the floor controller, the relative movement between the synchronizer and the advancer is utilized for controlling the acceleration and deceleration of the elevator car.

In the conventional floor controller in which the advancer is advanced to a position corresponding to a floor from which a call is originated, an increase in the rated speed of the elevator car results inevitably in an increase in the running distance required for the elevator car to attain this highest speed. Therefore, the advancer must be previously advanced by a distance corresponding to the running distance of the running elevator car. Suppose, for example, that the elevator car is rated to run at a speed of 540 meters per minute. In this case, the minimum running distance required for the elevator car to attain the speed of 540 meters per minute is of the order of 100 meters and this distance corresponds to the distance including about 30 floors of a building having floors vertically spaced apart by a pitch commonly employed in the art. Inasmuch as the elevator car makes vertical movement, the advancer must make its free advancing movement within a range which is twice the movable range thereof. Thus, the guide rail for the advancer supported on the synchronizer must have a correspondingly large length and the size of the floor controller is increased correspondingly.

The floor controller is generally installed in the machinery room disposed above the shaft. The floor con-

troller can be accommodated within the space limited by the ceiling of the machinery room when it is adapted for controlling an elevator car rated at a highest speed of the order of 400 meters per minute, but its height is increased to such an extent that it extends above the ceiling level of the machinery room when the rated speed of the elevator car is increased beyond the above value. On the other hand, elevator cars rated at a higher speed are demanded and this demand provides a serious problem.

It is therefore a primary object of the present invention to provide a small-sized elevator control apparatus or floor controller suitable for controlling a high-speed and high-lift elevator car.

In accordance with one aspect of the present invention, there is provided a floor controller comprising a synchronizer movable at a reduced speed proportional to the running speed of an elevator car servicing a plurality of service floor landings, an advancer disposed on said synchronizer so as to be movable within a predetermined range from the position of said synchronizer for detecting a floor originating a call, a pre-advancer movable within a range outside the movable range of said advancer for detecting another floor originating another call, and means for determining the running mode of the elevator car depending on the position of said synchronizer relative to the position of the call-originating floor detected by said pre-advancer or said advancer. The present invention having the feature above described is advantageous in that the size of the synchronizer and advancer, hence the overall size of the floor controller can be remarkably reduced and the floor controller can be accommodated within the machinery room with a large space margin even if it is adapted for controlling an elevator car operable with a high speed of the order of 540 meters per minute.

In accordance with another aspect of the present invention, there is provided a floor controller of the kind above described in which means for indicating call-originating floors are disposed on the frame of the floor controller so that the deceleration pattern which cannot be obtained on the basis of the positional relation between said advancer and said synchronizer during running of the elevator car at a high speed can be produced on the basis of the positional relation between said synchronizer and said means disposed on the frame of said floor controller. The present invention having the above feature is advantageous in that the small-sized floor controller can satisfy the functional demands described previously.

Other objects, features and advantages of the present invention will be apparent from the following detailed description of a preferred embodiment thereof taken in conjunction with the accompanying drawings, in which:

FIG. 14 is an electrical circuit diagram of a circuit for controlling call detection relays employed in the floor controller according to the present invention; and

FIG. 15 is an electrical circuit diagram of a circuit for energizing oscillating units employed in the floor controller according to the present invention.

Referring to FIG. 1 showing schematically the structure of a prior art floor controller for controlling an elevator car operating with a highest speed of 360 meters per minute in a building having 25 floors, a driving tape 1 is connected to the elevator car to be driven at a speed which is the same as the speed of the car. An output gear 2 of a reduction gear unit (not shown) is rotated at a reduced speed which is proportional to the running speed of the elevator car. A driving chain 4 is trained between the output gear 2 and an idler gear 3. A synchronizer 5 is vertically movably supported on a guide rail 6 and is driven by the driving chain 4 to make vertical movement at a reduced speed which is proportional to the running speed of the elevator car. Further, an advancer 7 is vertically movable on the synchronizer 5. A guide rail 8 for guiding the vertical movement of the advancer 7 is supported by supporting means 9 extending from the synchronizer 5. Although not shown, a miniature motor is mounted on the synchronizer 5 for causing vertical movement of the advancer 7 in advanced relation with respect to the synchronizer 5.

Suppose now that the elevator car has moved upward from the 1st floor and is at rest at the 13th floor. Due to the fact that the synchronizer 5 is moved in proportion to the movement of the elevator car, the synchronizer 5 is at rest with its central portion registering with the position corresponding to the 13th floor on the floor controller. (The numerals shown on the right-hand side of FIG. 1 represent the floor numbers.) Thus, the synchronizer 5 occupies the position shown by the solid lines in FIG. 1. The advancer 7 has been at rest at the position corresponding to the 13th floor as shown by the broken lines until the elevator car, hence the synchronizer 5 moving upward from beneath stops at the 13th floor position. The reference numeral 7'

designates such position of the advancer 7. When the elevator car moving upward stops at the 13th floor and the central portion of the synchronizer 5 registers with the advancer 7 resting at the position 7', the advancer 5 makes upward movement in a direction as shown by the arrow to be advanced relative to the synchronizer 5. The advancer 7 continues to move upward until it reaches a position corresponding to an upper floor from which a call is originated. Thus, when, for example, an up call shown by the symbol Δ is registered at the hall of the 21st floor, the advancer 7 moving upward stops at the position corresponding to the 21st floor. This means that the floor at which the elevator car should stop next is detected and this floor position is memorized. With the upward movement of the advancer 7, a detector on the advancer 7 detects successive detected elements disposed on the frame of the floor controller at positions corresponding to the floor positions, and means are provided for counting the number of the detected elements detected by the detector. This count represents the distance to be run next by the elevator car.

As is commonly known, the highest speed of an elevator car differs depending on the running distance, that is, the number of floors to be passed thereby. For example, an elevator car having an operating range of more than ten floors and rated at a highest speed of 360 meters per minute is accelerated to run with the speed of 90 meters per minute, 120 meters per minute and 150 meters per minute when it runs from, for example, the 1st floor to the 2nd floor, 3rd floor and 4th floor respectively, and the highest speed of 360 meters per minute is developed only when the elevator car runs from, for example, the 1st floor to a floor above and including the 11th floor without stopping at any intermediate floors. This is necessarily determined from the requirements including provision of a comfortable sense of ride for passengers and the distance required for acceleration and deceleration.

Suppose now that such an elevator car is controlled by the prior art floor controller shown in FIG. 1. In this case, the elevator car is instructed to run at a highest speed of 300 meters per minute due to the fact that the number of the elements detected by the detector on the advancer 7 is eight and the distance to be run by the elevator car is the range of from the 13th floor to the 21st floor. Thus, the first function of the floor controller is to detect the distance between the elevator car and the floor originating the call and to determine the highest speed at which the elevator car should run for reaching such floor.

The elevator car leaving the 13th floor is accelerated up to the speed of 300 meters per minute during its upward movement and is subsequently decelerated. In FIG. 1, the synchronizer 5 is now moved upward toward the advancer 7 which is at rest at the position shown by the solid lines. As is commonly known, the decelerating instruction signal is applied to the elevator car as a function of the position in order to minimize floor arrival errors. The curve shown at the left-hand side of FIG. 1 represents the deceleration pattern for the elevator car under the illustrated relation between the position of the advancer 7 and the position of the synchronizer 5 shown by the solid lines. The elevator car is gradually decelerated in the manner shown by the curve as a series of detectors 38 provided on the synchronizer 5 move past a detected element provided on

the advancer 7. Consequently, the synchronizer 5, hence the elevator car is stopped when the synchronizer 5 is moved upward to the position at which the central portion of the synchronizer 5 registers with the advancer 7 as seen from the deceleration pattern. (Actually, however, a position detector disposed in the shaft detects the physical position of the elevator car immediately before the elevator car is stopped so that the elevator car can be accurately stopped at the predetermined position.) Thus, the second function of the floor controller is to produce a deceleration pattern relative to the position of the elevator car. The synchronizer 5 may be utilized to serve also as a means such as an indicator indicating the position of the elevator car, but this is not the essential function of the floor controller.

The general outline of the floor controller can be understood from the above description, but a serious problem as described below arises in recent years. Due to the tendency toward construction of skyscrapers in recent years, elevator cars for servicing a longer service range are required and a higher speed is necessarily demanded. It is quite natural that a long distance run results in the increase in the height of the floor controller. The floor controller shown in FIG. 1 differs from actual one since FIG. 1 is merely a schematic representation of the structure of the floor controller. Even if the pitch between the floors depicted in a reduced scale in FIG. 1 were as illustrated, the floor controller would become considerably large in size as it will be apparent from the position of the synchronizer 5 when the elevator car stops at the 1st or 25th floor. As will be apparent from the broken lines showing the state of the synchronizer 5 stopping at the position corresponding to the 25th floor, the floor controller must have actually a considerably large vertical length which is quite greater than the distance of reduced scale corresponding to the actual distance between the 1st floor and the 25th floor.

Another problem arises from the fact that the increase in the highest speed results in the increase in the height of the floor controller. As will be seen from the example of the prior art floor controller shown in FIG. 1, the advancer 7 need not detect calls within the range of from the 1st to the 25th floor and may only detect a call or calls originated from the range of from the 1st to the 10th floor when the elevator car is at rest at the 1st floor. This is because the determination of the running speed of the elevator car is required only when the elevator car is instructed to run from, for example, the 1st floor to the 10th or lower floor due to the fact that the elevator car is designed to develop its highest speed of 360 meters per minute only when it runs from, for example, the 1st floor to the 11th or upper floor.

It may be seen from the above example that the floor number to which the advancer 7 should be advanced is inevitably increased when the highest speed of the elevator car exceeds 360 meters per minute. For example, when the elevator car is designed to run at a highest speed of 540 meters per minute, this highest speed can only be developed when the elevator car runs from, for example, the 1st floor to the 17th or upper floor provided that the speed can be increased at a rate of 30 meters per minute as the elevator car passes from one floor to another. Therefore, the running speed must be determined depending on the running distance when the elevator car services the range of less than sixteen

floors. Thus, the advancer 7 is requested to be capable of being advanced to the position beyond the position of the synchronizer 5 by the distance corresponding to 16 floors. One may easily seen from FIG. 1 that this results in a remarkable extension of the synchronizer 5 in the vertical direction and the height of the floor controller is remarkably increased to an extent that it is more than two times that designed for the highest speed of 360 meters per minute.

10 The present invention provides an improved floor controller having a remarkably reduced size. The basic principle of the present invention will be described at first with reference to FIG. 2.

Referring to FIG. 2, a pair of pre-advancers 42U and 42D are fixedly mounted on an advancer 7 so as to detect calls originated from the upper and lower floors than that detected by the advancer 7. The length of the arm of three pre-advancers 42U and 42D is determined so that the pre-advancers are movable over a range 15 which is greater than the movable distance of the advancer 7. The advancer 7 in the prior art floor controller shown in FIG. 1 has had a limit in its movement such that it can only be advanced to the position corresponding to the 11th floor when the synchronizer 5 is at rest at the position corresponding to the 1st floor. In the present invention, the pre-advancer 42U moves with the movement of the advancer 7 to a position corresponding to the 12th or upper floor when the synchronizer 5 and advancer 7 in FIG. 2 are shown entirely the same as those shown in FIG. 1.

Suppose now that the elevator car stands by at the 1st floor and up calls are originated from the 4th and 19th floors. Due to the fact that the elevator car stands by 35 at the 1st floor, the synchronizer 5 occupies also the position corresponding to the 1st floor on the floor controller. The advancer 7 having been standing at the 1st floor starts to move upward prior to the upward movement of the elevator car so as to detect calls originated from the upper floors. Similarly, the pre-advancer 42U starts to detect calls from the upper floors including the 12th floor. Since it is supposed that the calls ① and ② are only originated from the 4th and 19th floors respectively, the advancer 7 detects the call ① before the pre-advancer 42U detects the call ②. Therefore, the advancer 7 stops at the position corresponding to the 4th floor originating the call ① as in the case of the prior art floor controller. Thus, the pre-advancer 42U cannot make upward movement any more and the call ② is not detected thereby.

In this manner, when a plurality of calls are originated and the advancer 7 detects one of the calls before the pre-advancers 42U and 42D detect other calls, this call is the call which should be serviced by the elevator car at first, and the elevator car, hence the synchronizer 5 starts to move upward toward the advancer 7 which is at rest at the position corresponding to the floor from which this call is originated.

60 Consider next the case in which up calls ③ and ④ are originated from the 8th and 14th floors respectively. In such a case, the elevator car should move upward toward the 8th floor at first, and after stopping at the 8th floor and trying to detect other calls again, it should move upward toward the nearest upper floor from which a call is originated.

65 Referring to FIG. 2 again, the advancer 7 and pre-advancer 42U and 42D move upward and the call ④

originated from the 14th floor is first detected by the pre-advancer 42U, but the advancer 7 does not stop and continues to move upward. When the advancer 7 moving upward reaches the position corresponding to the 8th floor as shown by 7'', the advancer 7 stops at such position by detecting the up call ③ originated from the 8th floor. Circuit arrangement is such that any memory stored in a memory circuit due to previous detection of other calls by the pre-advancer 42U is erased when the advancer 7 detects a call as above described. Therefore, the elevator car starts to move upward toward the 8th floor in the manner above described. After stopping at the 8th floor, the elevator car starts call detection again and move upward from the 8th floor toward a floor from which another call is originated. In this manner, the pre-advancer 42U and 42D search for a call originated from the position which cannot be detected by the advancer 7 in order to deal with the high-speed operation. Upon detection of another call by the advancer 7, the memory stored in the memory circuit due to the detection of calls by the pre-advancers 42U and 42D is erased. When, for example, the calls ② and ④ are originated solely, the advancer 7 does not detect these calls even when it is advanced to the uppermost position of the synchronizer 5. In such a case only, the memory of the calls ② and ④ is derived from the memory circuit and the running speed of the elevator car is suitably determined so that the elevator car can make upward movement at a suitable speed to respond the first detected floor call.

It will be apparent from FIG. 2 that such an arrangement is advantageous in that calls can be detected over a range which is about two times the length of the guide 8 for the synchronizer 5 and the synchronizer 5 having a size similar to that shown in FIG. 1, can control the operation of an elevator car designed for running at a very high speed. Further, as seen in FIG. 2, the overall size of the floor controller is quite small due to the fact that the preadvancer 42D is positioned opposite to the position of the lower supporting means 9 for the synchronizer 5 in the prior art floor controller even when the advancer 7 is at rest at the position corresponding to the 1st floor which is the bottom terminal of the elevator. In the prior art floor controller shown in FIG. 1 many detectors 38 are disposed on the synchronizer 5 opposite to the advancer 7 so as to obtain the deceleration pattern for the elevator car. However, it is impossible to obtain the deceleration pattern with such arrangement due to the fact that, in the present invention, the deceleration pattern is also required in the range beyond the length of the synchronizer 5. In the present invention, the deceleration pattern is produced in a manner similar to that described with reference to FIG. 1 when the speed of the elevator car is relatively low. In a higher speed range, however, the desired deceleration pattern is produced by the combination of a group of additional detectors disposed on the synchronizer 5 and a group of detected elements disposed on the controller frame opposite to the detectors. More precisely, due to the fact that the deceleration pattern cannot be produced on the basis of the positional relation between the synchronizer 5 and the advancer 7 when the elevator car runs over a distance greater than the distance corresponding to the length of the synchronizer 5, a group of detectors for generating the deceleration pattern for the high-speed operation (long distance

operation) are disposed on the synchronizer 5 within the extent of the synchronizer 5 in a relationship suitably displaced from the floor positions and a group of detected elements for indicating call-originating floors are disposed on the controller frame at correspondingly displaced positions. These detected elements are provided for all the floors respectively so that, when the floor to be serviced next by the elevator car is determined by the call detecting action of the advancer or pre-advancers, the detected element corresponding to that floor can be solely detected. Thus, the deceleration pattern for the elevator car can be produced over all the speed range in spite of the fact that the synchronizer 5 is small in size.

In the foregoing description, the numerical values including those of the size and speed are merely given for illustrative purposes for the ease of understanding and differ from the actual values. An embodiment of the present invention will be described in detail with reference to FIGS. 3 to 15.

FIG. 3 is a perspective view of one form of the floor controller according to the present invention. Referring to FIG. 3, a driving tape 1 is connected to an elevator car and is driven at the same speed as that of the elevator car. An output gear 2 of a reduction gear unit (not shown) is rotated at a reduced speed which is proportional to the running speed of the elevator car. A driving chain 4 is trained between an idler gear 3 and the output gear 2. A synchronizer 5 is vertically movably supported on a guide rail 6 and is driven by the driving chain 4 to make vertical movement at a reduced speed which is proportional to the running speed of the elevator car. An advancer 7 is vertically movable on the synchronizer 5. A guide rail 8 for guiding the vertical movement of the advancer 7 is supported by supporting means 9 extending from the synchronizer 5. The advancer 7 is suspended from one end of a chain 10 which is trained around a gear (not shown) and a balance weight is suspended from the other end of the chain 10. A motor 11 is mounted on the synchronizer 5 for causing vertical movement of the advancer 7 through a rack-pinion unit (not shown).

An oscillator 12 is mounted on the synchronizer 5 for detecting the position of the synchronizer 5, and a receiver 41 is mounted on the synchronizer 5 for detecting the decelerating point. The oscillator 12 consists of a pair of juxtaposed oscillating units 12L and 12R. The receiver 41 consists of two groups of receiving units 41GU and 41GD for receiving a signal during upward movement and downward movement of the elevator car respectively. A solid-state miniature oscillator is incorporated in each of these oscillating units 12L and 12R and is continuously oscillating without any mal-operation even in a severe environment. A solid-state miniature receiver is incorporated in each of the receiving units 41GU and 41GD so that each receiving unit receives a signal from one of oscillating units 41X described later and applies a signal to a control circuit only when the receiving unit is opposed by the oscillating unit.

Oscillators 13 and 42 are mounted on the advancer 7 for detecting the position of the advancer 7. The oscillator 13 is divided into a pair of an upper oscillating unit 13U and a lower oscillating unit 13D. The oscillator 42 consists of a pair of vertically spaced oscillating units 42U and 42D. These oscillating units 42U and 42D are disposed at positions vertically spaced from

the oscillator 13 by a suitable distance so that they can be advanced relative to the advancer 7 on the synchronizer 5.

A plurality of means 41XU, 41XD, 14, 15 and 42X are fixedly provided on the frame of the floor controller at a position corresponding to each of the floors serviced by the elevator car. The stationary means 14 consists of pairs of receiving units 14L and 14R arranged in two vertical series opposite to the respective oscillating units 12L and 12R, and each pair of these receiving units 14L and 14R are disposed at a position corresponding to each of the floors. However, the position of these receiving units 14L and 14R is adjustable in the vertical direction. The stationary means 15 and 42X represent receiving units disposed at a position corresponding to each of the floors. The stationary means 41XU and 41XD represent oscillating units mounted on the controller frame opposite to the respective receiving units 41GU and 41GD, and the number of these oscillating units is equal to the number of the floors. However, these oscillating units 41XU and 41XD are not disposed at the exact position corresponding to each of the floors and they are displaced downward and upward respectively relative to the exact floor position by a predetermined distance. Although only one set of the stationary means 14, 15 and 42X corresponding to one floor is shown in FIG. 3, the number of sets of these means is equal to the number of the floors serviced by the elevator car. Thus, each time the elevator car arrives at one of the floors, the specific stationary means or receiving units 14, 15 and 42X are opposed by the movable means or oscillators 12, 13 and 42 so that an output signal appears from these stationary means 14, 15 and 42X.

The relation between the stationary means or oscillating units 41XU, 41XD and the receiving units 41GU, 41GD is such that the oscillating unit 41XU is opposed by the receiving unit 41GU at a predetermined point beneath each floor level when the elevator car is moving upward and the oscillating unit 41XD is opposed by the receiving unit 41GD at a predetermined point above each floor level when the elevator car is moving downward, so that output signals appear successively from the receiving units 41GU and 41GD depending on the moving direction of the elevator car. Thus, these movable means and stationary means operate as a contactless position detecting means.

The movable means 13 and 42 provided on the advancer 7 are advanced beyond the actual position of the elevator car as the advancer 7 is driven by the motor 11, and the advancer 7 is stopped at the position corresponding to the floor from which a call is originated. The movable means 12 and 41 provided on the synchronizer 5 follow the movement of the movable means 13 and 42 with in suitably delayed relation. Further, contactless type relative position detecting means which will be described later are provided for detecting the difference between the relative positions of the advancer 7 and the synchronizer 5 arranged for vertical movement in synchronism with the movement of the elevator car.

A magnet 19 is mounted on the synchronizer 5. In response to the energization of the magnet 19, an armature 20 is attracted to the magnet 19 and makes pivotal movement around a pivot pin 21. As a result, an enlarged portion 22 of the armature 20 presses against abutment members 25 and 26 provided on cranks 23

and 24 (FIG. 4) thereby causing rotation of crankshafts 27 and 28 clockwise and counterclockwise respectively. Consequently, engaging members 29 and 30 supported by the advancer 7 are rotated clockwise and counterclockwise respectively thereby causing extension of a return spring 31. A bar 32 extends vertically within the housing of the floor controller, and stoppers 33 are mounted on the bar 32 at positions corresponding to the actual floor levels serviced by the elevator car, although only one of such stoppers 33 is shown in FIG. 3.

FIG. 4 is an enlarged perspective view showing parts of FIG. 3 in detail, and parts bearing the same reference numerals as those shown in FIG. 3 have been already described. A mounting arm 35 extends horizontally from the advancer 7 and an oscillating unit 36 of a contactless switch is mounted on the mounting arm 35. A mounting plate 37 is fixed to the synchronizer 5 and a vertical series of receiving units 38 are mounted on the mounting plate 37 opposite to the oscillating unit 36.

The oscillating unit 36 and receiving units 38 are arranged in a manner as shown in FIG. 5 for detecting the distance D between the synchronizer 5 and the advancer 7. During upward movement of the elevator car, the oscillating unit 36 carried by the advancer 7 is advanced upward to the position corresponding to the floor from which a call is originated. Subsequently, the receiving units 38U₉, . . . 38U₂ and 38U₁ carried by the synchronizer 5 are successively brought to the position opposite to the oscillating unit 36 with the upward movement of the synchronizer 5, and when the elevator car stops at the target floor, the oscillating unit 36 takes the neutral position C. During downward movement of the elevator car, the oscillating unit 36 carried by the advancer 7 is advanced downward, and subsequently, the receiving units 38D₉, . . . 38D₂ and 38D₁ carried by the synchronizer 5 are successively brought to the position opposite to the oscillating unit 36 with the downward movement of the synchronizer 5. The oscillating unit 36 and receiving units 38 constitute a relative position detecting means which detects the distance between the synchronizer 5 and the advancer 7 for generating a deceleration instruction signal. Receiving units 38UL and 38DL are disposed at the opposite extremities of the vertical advancing movement of the advancer 7 relative to the synchronizer 5 so that the oscillating unit 36 can be opposite by these receiving units at such extreme positions.

FIG. 6 shows the arrangement of the oscillating units 41XU, 41XD and receiving units 41GU, 41GD. The oscillating units 41XU and 41XD are mounted on the controller frame in the number equal to the number of the floors. One or ones of these oscillating units 41XU and 41XD oscillate only when a call or calls are originated from the corresponding floor or floors and the remaining oscillating units do not oscillate as will be described later. These oscillating units 41XU and 41XD are used to detect the relative positions between them and the synchronizer 5. When the elevator car is designed to run at a high rated speed of, for example, 540 meters per minute, a distance of about 50 meters is required for deceleration. Suppose that a 1:100 reduced scale is employed, then a deceleration distance of about 500 millimeters is required on the floor controller. This means that D in FIG. 5 must be larger than about 500 millimeters. Taking the vertical movement

into consideration, a distance of $2 \times D$ is required at least at this distance amounts to about 1 meter at the least. This means that the guide rail 8 for the advancer 7 must have a larger length and the size of the floor controller is increased correspondingly. In the present invention, in order to eliminate the above drawback, D in FIG. 5 is selected to be about one-half of D corresponding to the deceleration distance required for the elevator car rated at a high speed of, for example, 540 meters per minute, and the oscillating units 41XU, 41XD and receiving units 41GU, 41GD are utilized for compensating for the reduction of the distance D.

Suppose now that the elevator car servicing 40 floor landings of a building stands by at the 1st floor and a call is originated from the 35th floor. In this case, the oscillating unit 41XU₃₅ corresponding to the 35th floor oscillates and the elevator car starts to move upward toward the 35th floor. During upward movement of the elevator car toward the 35th floor, the receiving units 41GU_n, ..., 41GU₁ are successively brought to the position opposite to the oscillating unit 41XU₃₅ thereby detecting the relative positions of the 35th floor and the elevator car for deceleration. The advancer 7 is advanced to be stopped at the position corresponding to the 35th floor, and subsequently, the receiving units 38U₉, ..., 38U₁ are successively brought to the position opposite to the oscillating unit 36 in FIG. 5 thereby detecting the relative positions of the advancer 7 and the synchronizer 5, hence the elevator car. It will thus be seen that the deceleration pattern is produced by the combination of the oscillating units on the controller frame and the receiving units on the synchronizer 5 in the range in which the elevator car is sufficiently remote from the target floor and is running at a high speed, while in the low speed range in which the elevator car approaches the zone relatively near the target floor, the deceleration pattern is produced by the combination of the oscillating unit on the advancer 7 and the receiving units on the synchronizer 5.

Referring to FIG. 4, a shielding plate detector 39 is secured to the mounting arm 35 extending from the advancer 7 to constitute a zone position detector 44 together with shielding plates 43 arranged in a vertical series on a bar 40 extending vertically within the controller housing. The number of these shielding plates 43 is equal to the number of the floors of the building although only two of them are shown in FIG. 4. Since the shielding plates 43 are disposed at positions corresponding to the floors, an output signal appears from the shielding plate detector 39 during the period of time in which the advancer 7 is present in the predetermined zone including the corresponding floor.

FIG. 7 shows schematically the structure of the zone position detector 44. In the state in which the shielding plate 43 is not inserted into the gap between a feedback coil L₃ and an input coil L₁, these coils L₃ and L₁ are magnetically coupled and an output appears from an output coil L₂. Thus, no output appears at an output terminal E(0) of a logic circuit 44L and an output appears at another output terminal C(0) of the logic circuit 44L. When the shielding plate 43 is inserted into the gap, the magnetic coupling between the coils L₃ and L₁ is substantially lost and no output appears from the output coil L₂. In this case, an output appears at the output terminal E(0) and no output appears at the output terminal C(0).

FIG. 8 shows the output waveforms of the zone position detector 44 and of a waveform converter in a control circuit described later for generating a speed instruction signal in response to the application of the zone position detector output.

FIG. 9 shows the relation between the means for detecting the position of the synchronizer 5 relative to the position of the advancer 7 and means for generating such a deceleration instruction signal which cannot be obtained with the relative position detecting means depending on the relation between the shielding plate detector 39 and the shielding plates 43 and on the positional relation between the synchronizer 5 and the oscillating units 41XU and 41XD mounted on the frame 15 of the floor controller. In FIG. 9, only those means associated with the upward movement are shown. The detection of the relative positions of the advancer 7 and the synchronizer 5 and the operation of the zone position detector 44 consisting of the shielding plate detector 39 and shielding plates 43 have been described already.

The receiving units 41GU₁ to 41GU_n shown in FIG. 9 serve for giving a deceleration instruction signal during upward movement of the elevator car. In the present embodiment, for example, the receiving units 41GU₄, 41GU₃, 41GU₂ and 41GU₁ are adapted to give the deceleration instruction signal for decelerating the speed of the elevator car from 450 m/min, 420 m/min, 390 m/min and 360 m/min respectively and are 25 mounted on the synchronizer 5 at suitably spaced predetermined positions. These receiving units 41GU are disposed opposite to the oscillating units 41XU and the number of these receiving units 41GU is equal to the number of the floors. The receiving units 41GU used in the upward movement of the elevator car are displaced downward by a predetermined distance from the position 30 corresponding to the floors of the building.

Suppose now that a call is originated from the 40th floor and the elevator car stands by at the 1st floor. 40 Suppose further that the elevator car moving upward from the 1st floor while being accelerated toward the 40th floor in response to the call is running at a speed of 450 m/min. In response to the detection of the call by the elevator car, a circuit described later is ready for generating a deceleration instruction signal and the oscillating unit 41XU₄₀ corresponding to the 40th floor is solely energized. During upward movement of the elevator car, a deceleration instruction signal for decelerating the speed of the elevator car to 420 m/min from 450 m/min is generated due to the fact that the receiving unit 41GU₄ is brought to the position opposite to the oscillating unit 41XU₄₀. Then, the receiving unit 41GU₃ is brought to the position opposite to the oscillating unit 41XU₄₀ and a deceleration instruction signal is generated for decelerating the speed to 390 m/min from 420 m/min. In this manner, the receiving units 41GU₄, 41GU₃, ..., 41GU₁ are successively brought to the position opposite to the oscillating unit 41XU₄₀ 45 corresponding to the 40th floor originating the call so that the speed of the elevator car is reduced to less than 360 m/min. When the advancer 7 is advanced to the position corresponding to the 40th floor, the magnet 19 is deenergized and the engaging member 29 engages the stopper 33 corresponding to the 40th floor thereby stopping the advancer 7 at the position corresponding to the 40th floor. Then, when the synchronizer 5 moves 50 upward to reach the point at which the speed of the ele-

vator car is decelerated to less than 330 m/min, the receiving unit 38U₉ carried by the synchronizer 5 is brought to the position opposite to the oscillating unit 36 carried by the advancer 7 as described with reference to FIG. 5 and a deceleration instruction signal is generated. In this manner, deceleration instruction signals are successively generated from the receiving units 38U₈, 38U₇, . . . 38U₁ and the elevator car is gradually decelerated to arrive at the 40th floor.

FIG. 10 shows a control circuit for generating the speed instruction signal utilizing the output of the zone position detector 44 described with reference to FIGS. 7 and 8. The zone position detector 44 applied its output to a waveform converter M. The input and output waveforms of the waveform converter M are as shown in FIG. 8. The outputs appearing at the output terminals U and V of the waveform converter M are applied to the gate of thyristors THY₁ to THY₁₃. Speed instruction relays 21F to 33F apply a signal to the elevator speed control system in response to the energization thereof for controlling the speed of the elevator car. For ease for understanding, it is supposed that the speed instruction relays 21F, 22F, 23F, 24F, 25F, 26F, 27F, 28F, 29F, 30F, 31F, 32F and 33F are adapted to give speed instructions of 90 m/min, 120 m/min, 150 m/min, 180 m/min, 210 m/min, 240 m/min, 270 m/min, 300 m/min, 330 m/min, 360 m/min, 390 m/min, 420 m/min and 450 m/min respectively. Another speed instruction relay 20F applies a signal to the speed control system for smoothly accelerating the elevator car when the elevator car starts to move. This relay 20F is deenergized due to the opening of a contact LS when the elevator car being gradually decelerator reaches a point spaced by a predetermined distance from the target floor. Operation of contacts 90F, 90P and 90C will be described later.

FIG. 11 shows a deceleration control circuit. Deceleration instruction relays 21D to 33D in this circuit control the speed instruction relays 21F to 33F shown in FIG. 10. Thyristors THYU₁ to THYU₉ and THYD₁ to THYD₉ among thyristors THYU₁ to THYU₁₃ and THYD₁ to THYD₁₃ are controlled by the respective receiving units 38U₁ to 38U₉ and 38D₁ to 38D₉ described with reference to FIGS. 5 and 9. The remaining thyristors THYU₁₀ to THYU₁₃ and THYD₁₀ to THYD₁₃ are controlled by the respective receiving units 41GU₁ to 41GU₄ and 41GD₁ to 41GD₄ described with reference to FIGS. 3 and 6. It will be seen therefore that, when the elevator car is running upward at a speed of 450 m/min, the deceleration instruction signal is successively applied to the gate of the thyristors THYU₁₃, THYU₁₂, . . . THYU₁ and the deceleration instruction relays 33D, 32D, . . . 21D are successively energized for gradually decelerating the elevator car.

FIG. 12 shows a floor relay control circuit for controlling a group of floor relays 301A, 302A (not shown), . . . 309A, 310A, . . . 339A and 340A. Thyristors THYE₁ to THYE₄₀ are controlled by the receiving units 42X which generate a signal when opposed by the oscillating unit 42U or 42D which is spaced from a predetermined distance from the oscillator 13 as shown in FIG. 3. The oscillating unit 42U is energized only when the elevator car moves upward, while the oscillating unit 42D is energized only when the elevator car moves downward. The number of the receiving units 42X is equal to the number of the floors, and that for the 1st floor is designed herein by 42X₁, while that

for the *n*th floor is designated herein by 42X_n for ease of understanding.

Suppose, for example, that the elevator car is instructed for upward movement and the advancer 7 is at rest at the position corresponding to the 1st floor with the oscillating unit 42U opposed by the receiving unit 42X₁₀ before call detection relays 90C and 90F described later are energized. In this case, the thyristor THYE₁₀ is turned on to energize the 10th floor relay 310A in FIG. 12. Then, when the advancer 7 is advanced upward by a predetermined distance to reach a point in the vicinity of the position corresponding to the 2nd floor, the relay 311A is energized. It is so arranged that the floor relay having been energized solely holds itself in response to the energization of the call detection relays and the remaining floor relays are kept from being energized. A contact 15Z is closed only when the elevator car is in operation.

FIG. 13 shows a floor relay control circuit for controlling another group of floor relays 301, 302, . . . 339 and 340. Thyristors THYG₁ to THYG₄₀ shown in FIG. 13 are energized by the signal applied from the group of the receiving units 15-1, 15-2, . . . 15-40 provided on the floor controller frame opposite to the oscillator 13 mounted on the advancer 7 (FIG. 3). As described with reference to FIG. 5, the oscillating unit 36 is brought to the position opposite to the receiving unit 38UL when the advancer 7 is advanced to its upward extremity of the range in which the advancer 7 is movable on the synchronizer 5. When the oscillating unit 36 reaches such position, a thyristor THYF in FIG. 13 is controlled by the receiving unit 38UL for energizing a relay 90P.

Suppose, for example, that the elevator car standing by at the 1st floor starts to move upward toward the 39th floor in response to a call originated from the 39th floor. Before the advancer 7 is advanced, that is, when the advancer 7 takes the position corresponding to the 1st floor, the oscillating unit 13U, which is mounted on the advancer 7 and is energized during upward movement of the elevator car, is opposite to the receiving unit 15-1 corresponding to the 1st floor in the group of the receiving units 15, and the oscillating unit 42U is opposite to, for example, the receiving unit 42X₁₀ corresponding to the 10th floor. Thus, the floor relays 301 and 310A are energized in FIGS. 13 and 12 respectively. The relay 90P is still in the deenergized state due to the fact that the advancer 7 is not yet advanced to its upward extremity. The energization of the floor relay 310A results in energization of the floor relay 310 since the call detection relay 90F described later is still in the deenergized state. Thus, in the state in which the advancer 7 is not yet advanced to its upward extremity and the relay 90P remains deenergized, the floor relays in FIG. 13 are successively energized as the receiving units 15 and 42X are successively opposed by the oscillating units 13U and 42U.

In the range in which the advancer 7 is advanced by a distance corresponding to, for example, nine floors relative to the synchronizer 5, one of the floor relays corresponding to the receiving unit 42X opposite to the oscillating unit 42U is energized in FIG. 12 and two of the floor relays corresponding to the receiving units 15 and 42X opposite to the oscillating units 13U and 42U are energized in FIG. 13. Then, when the advancer 7 is advanced to the predetermined upward extremity and the oscillating unit 36 is brought to the position op-

posite to the receiving unit 38UL in FIG. 5, the thyristor THYF is turned on to energize the relay 90P in FIG. 13. In response to the energization of the relay 90P, the floor relays 301, 302, . . . 340 are deenergized in FIG. 13 even when the receiving units 15 apply the signal to the gate of the thyristors THYG. Therefore, one of the floor relays 301A, 302A, . . . 340A corresponding to the receiving unit 42X opposite to the oscillating unit 42U is solely energized in FIG. 12, and then, one of the floor relays 301, 302, . . . 340 corresponding to the same floor is solely energized in FIG. 13. After the advancer 7 has been advanced to the predetermined upward extremity of advancing movement on the synchronizer 5 and the relay 90P has been energized, the motor 11 is deenergized and the synchronizer 5 moves upward while maintaining the predetermined distance between it and the advancer 7.

When the oscillating unit 42U mounted on the advancer 7 is brought to the position opposite to the receiving unit 42X₃₉ corresponding to the 39th floor, the thyristors THYE₃₉ is turned on to energize the floor relay 339A in FIG. 12 and the floor relay 339 is energized in FIG. 13. Due to the fact that a call is originated from the 39th floor, the call detection relay 90F in a circuit described later is energized to establish a self-holding circuit for the floor relay 339A and the floor relay 339 is deenergized in response to the energization of the call detection relay 90F. When the oscillating unit 13U mounted on the advancer 7 is brought to the position opposite to the receiving unit 15-39 corresponding to the 39th floor as a result of a continuous upward movement of the elevator car toward the 39th floor, the thyristors THYG₃₉ in FIG. 13 is turned on to energize an auxiliary call detection relay 90S through the contact of the floor relay 339A and this auxiliary call detection relay 90S holds itself until the elevator car stops at the target floor.

Referring to FIG. 14 showing a circuit for controlling the call detection relays 90C and 90F, contacts 501 to 540 corresponding to the 1st to 40th floor respectively are selectively closed when a call is originated from the corresponding floor. The reference numerals 301 to 340 and 301A to 340A designate the contacts of the floor relays 301 to 340 and 301A to 340A respectively. A thyristor THYH is turned on only when the shielding plate 43 in the zone position detector 44 shown in FIG. 7 is in the illustrated position. The call detection relay 90F is energized in response to the detection of a call by the floor relays 301A, 302A, . . . 340A which are controlled by the oscillator 42 mounted on the advancer 7, hence the oscillating units 42U and 42D which are fixed at the predetermined positions vertically spaced from the center of the advancer 7. In other words, this call detection relay 90F is initially energized when a call is originated from a floor which is spaced by more than nine floors from the floor at which the elevator car is at rest. The call detection relay 90C is energized when the advancer 7 reaches the position corresponding to the floor from which the call is originated and the elevator car can stop at such floor. In response to the energization of the relay 90C, the magnet 19 in FIG. 3 is deenergized thereby releasing the armature 20 and causing retracting movement of the enlarged portion 22 of the armature 20. As a result, the crankshaft 27 is rotated counterclockwise and the engaging member 29 engages the stopper 33 corresponding to the tar-

get floor for stopping the advancer 7 at the position corresponding to the target floor.

FIG. 15 shows a circuit for energizing the oscillating units 41XU shown in FIG. 9 which are used for upward movement of the elevator car. Although the oscillating units 42XD used for downward movement are not shown in FIG. 9 for avoiding confusion, it is apparent that these units 42XD are similarly arranged. These oscillating units 42XU are energized when the elevator car runs upward at a speed higher than 360 meters per minute. When, for example, the elevator car is instructed to run over a distance of more than nine floors, the relays 90P and 90F are energized to energize the oscillating unit 42XU_n corresponding to the nth floor at which the elevator car is instructed to stop. A contact 15Z is closed only when the elevator car moves upward.

The elevator control apparatus according to the present invention controls the elevator car in a manner as described below.

Suppose now that the elevator car stands by at the 1st floor and a passenger waiting at the 39th floor depresses the hall button at the 39th floor landing or a passenger in the elevator car depresses the push button corresponding to the 39th floor. In response to the depression of the button, the call detection relay 90F is energized by a circuit (not shown) and the contact 539 is closed in FIG. 14. Due to the fact that the elevator car stands by at the 1st floor, the shielding plate 43M₁ corresponding to the 1st floor is opposite to the shielding plate detector 39 as will be apparent from FIG. 4. Running direction selecting means (not shown) is energized to detect the fact that this call is originated from the floor above the floor position of the elevator car and generates a signal for causing upward movement of the elevator car. The contact 15Z is closed and the motor 11 shown in FIG. 3 is rotated in the normal direction to advance the advancer 7 relative to the synchronizer 5. Further, due to the closure of the contact 15Z, the speed instruction relay 20F is energized in FIG. 10 and the resetting signal for the waveform converter M disappears so that the elevator car is now ready to move upward.

The advancer 7 starts to move upward on the synchronizer 5, and as soon as the shielding plate detector 39 moves out of the range of the shielding plate 43M₁ corresponding to the 1st floor, inversion occurs in the detector outputs appearing at the output terminals E(0) and C(0), but no change occurs in the outputs appearing at the output terminals U and V of the waveform converter M. Therefore, the output appears solely at the output terminal U of the converter M to be applied to the gate of the thyristors THY, but the relays 21F and 30F are solely energized due to the interlocking of the terminals. When the shielding plate detector 39 is brought to the position opposite to the shielding plate 43M₂ corresponding to the 2nd floor with the advancing movement of the advancer 7, the outputs appearing at the output terminals U and V of the waveform converter M are inverted with the result that the relays 22F and 31F are now selectively energized.

In this manner, on-off of the outputs of the shielding plate detector 39 is alternately repeated resulting in repeated on-off of the outputs appearing at the output terminals U and V of the waveform converter M as the shielding plate detector 39 moves past the shielding plates 43 corresponding to the successive floors. Thus,

the speed instruction relays are successively energized and hold themselves in the order of 21F and 30F, 22F and 31F, 28F and 32F, . . . These speed instruction relays 21F, 22F, . . . are provided to merely determine the highest running speed of the elevator car, and integrators (not shown) are provided for attaining gradual acceleration of the elevator car to give a comfortable sense of ride for passengers. The speed of the elevator car reaches finally the setting determined by these speed instruction relays.

In the meantime, with the movement of the advancer 7, the floor relays 301, 310A and 310; 302, 311A and 311; . . . are successively energized as described with reference to FIGS. 12 and 13. (In the present invention, it is supposed that the advancer 7 can be advanced on the synchronizer 5 by the distance corresponding to, for example, nine floors, and therefore, the oscillating unit 42U is mounted at the position which is advanced by the distance corresponding to nine floors relative to the oscillating unit 13U. Further, for convenience of description, it is supposed that the floors of the building are spaced apart by the same pitch. However, the floors may be spaced apart by a different pitch.) When the advancer 7 is advanced to the predetermined upward extremity of the movable range on the synchronizer 5, the relay 90P is energized as described with reference to FIG. 13. The relays 30F to 33F are kept energized until this relay 90P is energized due to the fact that the contacts 90C and 90F of the call detection relay 90C and 90F are kept closed, in FIG. 10. Thus, the running speed of the elevator car is determined so that it runs at the highest speed of 450 meters per minute.

The floor relay 339A is energized as described with reference to FIG. 12 when the oscillating unit 42U mounted on the advancer 7 is brought to the position opposite to the receiving unit 42X₃₉ corresponding to the 39th floor. In response to the energization of this floor relay 339A, the floor relay 339 is energized in FIG. 13 and the call detection relay 90F is also energized in FIG. 14. The floor relay 339A holds itself due to the energization of the call detection relay 90F and the oscillating unit 41XU₃₉ corresponding to the 39th floor is thereby energized in FIG. 15. With the upward movement of the elevator car, the receiving unit 41GU₄ is first brought to the position opposite to the oscillating unit 41XU₃₉, and then the receiving units 41GU₃, . . . are successively brought to the position opposite to the oscillating unit 41XU₃₉ as described with reference to FIG. 6. Therefore, the deceleration instruction relays 33D, 32D, 31D and 30D are successively energized at the predetermined decelerating points as described with reference to FIG. 11. As a result, the speed instruction relays 33F, 32F, 31F and 30F are successively deenergized in FIG. 10 and the elevator car is decelerated. Finally, the oscillating unit 13U mounted on the advancer 7 is brought to the position opposite to the receiving unit 15-39 corresponding to the 39th floor and the auxiliary call detection relay 90S is energized by the circuit which is traced from the positive terminal P—90S—339A—THYG₃₉ to the negative terminal N in FIG. 13 thereby energizing the call detection relay 90C in FIG. 14. In response to the energization of the call detection relay 90C, the magnet 19 in FIG. 3 is deenergized and the engaging member 29 engages the stopper 33 corresponding to the 39th floor to stop the advancer 7 at the position corresponding to the 39th floor.

The energization of the call detection relay 90C results in closure of the contact 90C in FIG. 11. When, with the upward movement of the elevator car, the oscillating unit 36 is brought to the position opposite to the receiving unit 38U₉ in FIGS. 9 and 5, the thyristor THYU₉ is turned on to energize the deceleration instruction relay 39D in FIG. 11. In this manner, the relays 28D, 27D, . . . 21D are successively energized to deenergize the relays 29F, 28F, . . . 21F successively with the result that the speed of the elevator car is gradually reduced to reach the speed of 90 meters per minute determined by the relay 21F. When the elevator car moving upward reaches a predetermined point beneath the level of the target floor, position detecting means (not shown) disposed in the shaft is energized to apply decelerating and stopping instructions to the speed control system depending on the distance between the elevator car and the target floor level so that the elevator car is decelerated to stop at the target floor.

The operation of the elevator control apparatus according to the present invention will be described with regard to the case in which the elevator car stands by at the 1st floor and a call is originated from the 11th floor.

The speed instruction relays are similarly successively energized with the advancing movement of the advancer 7. When the advancer 7 is advanced from the position corresponding to the 1st floor to the position corresponding to, for example, the 2nd floor, the oscillating unit 42U carried by the advancer 7 is brought to the position opposite to the receiving unit 42X₁₁ corresponding to the 11th floor and the call detection relay 90F is energized. Therefore, the speed instruction relays 21F and 30F are first energized, and then, the speed instruction relays 22F and 31F are energized. However, due to the energization of the call detection relay 90F, the relays 32F and 33F cannot be energized although the relays 23F, 24F, . . . 29F are successively energized with the advancing movement of the advancer 7. Thus, the elevator car runs at the speed of 390 meters per minute. Suppose that no calls are originated from the range of from the 2nd to the 10th floor. Due to the fact that a call is originated from the 11th floor, the call detection relay 90P is energized in FIG. 13 and the floor relay 311A corresponding to the 11th floor holds itself in FIG. 12 as described previously. When the advancer 7 is advanced to the position corresponding to the 11th floor, the relay 90S is energized in FIG. 13 by the circuit which is traced from the positive terminal P—90S—311A—THYG₁₁ to the negative terminal N thereby energizing the call detection relay 90C in FIG. 14. Thus, the elevator car is gradually decelerated to arrive at the 11th floor in the manner described previously.

Consider further the case in which the elevator car stands by at the 1st floor, a call is originated from the 11th floor, and another call is originated from, for example, the 5th floor which is included in the movable range of the advancer 7 on the synchronizer 5. When the advancer 7 is advanced from the position corresponding to the 1st floor to the position corresponding to the 2nd floor, the floor relay 311A is energized in FIG. 12 and the relay 90F is energized in FIG. 14 so that the floor relay 311A holds itself. At the time at which the relay 90F is energized, the speed instruction relays 20F, 21F, 22F, 30F and 31F have been energized in FIG. 10. When the advancer 7 is advanced to the po-

sition corresponding to the 5th floor, the floor relay 305 is energized by the circuit which is traced from the positive terminal P — 305 — 90P — E5 — THYG, to the negative terminal N in FIG. 13 although such elements are not shown in FIG. 13, and the relay 90C is energized by the circuit which is traced from the positive terminal P — 15Z — 90C — THYH — 90P — 305A — 305 — 505 to the negative terminal N in FIG. 14 although such elements are also not shown in FIG. 14.

At the time at which the advancer 7 is advanced to the position corresponding to the 5th floor, the speed instruction relays 20F, 21F, 22F, 23F, 24F and 25F have been successively energized, and the speed instruction relays 30F, 31F, 32F and 33F have also been successively energized. However, due to the fact that the advancer 7 is only advanced by the distance corresponding to four floors, the relay 90P is not energized. Further, due to the fact that the speed instruction relay 29F is not also energized, the speed instruction relays 30F to 33F are deenergized due to the energization of the call detection relay 90C. As a result, the speed instruction relays 20F, 21F, . . . 25F are selectively energized and the elevator car runs at the speed of 210 meters per minute. Due to the energization of the call detection relay 90C, the elevator car is gradually decelerated to stop at the 5th floor as will be apparent from the previous description. The operation of the elevator control apparatus in the case of downward movement of the elevator car is entirely the same as that described for upward movement and any description will be unnecessary.

The distance required for the deceleration and stoppage of an elevator car will increase in the form of a quadratic curve with the increase in the speed of the elevator car to, for example, 450 or 540 meters per minute. Further, the advanced distance of the advancer will increase also in the form of a quadratic curve in order to control the operation of such a high-speed elevator car. In the present invention which eliminates the undesirable increase in the distance above described, the oscillating units 42U and 42D are disposed at positions which are advanced relative to the central oscillator 13 by substantially the maximum advanced distance of the advancer 7, and the receiving units 41GU, 41GD and oscillating units 41XU and 41XD are separately provided to decelerate the elevator car in the high speed range of more than 360 meters per minute, so that the speed control up to the speed of the order of 540 meters per minute can be successfully attained without increasing the advanced distance of the advancer 7.

What is claimed is:

1. An elevator control apparatus comprising a synchronizing movable at a reduced speed proportional to the running speed of an elevator car servicing a plurality of service floor landings, an advancer disposed on said synchronizer so as to be movable within a predetermined range from the position of said synchronizer for detecting a floor originating a call, a pre-advancer movable within a range outside the movable range of said advancer for detecting another floor originating

another call, and means for determining the running mode of the elevator car depending on the position of said synchronizer relative to the position of the call-originating floor detected by said pre-advancer or said advancer.

2. An elevator control apparatus comprising means for indicating floors originating calls on a reduced scale representative of the service zone of an elevator car servicing a plurality of service floor landings, a synchronizer movable at a reduced speed proportional to the running speed of the elevator car, an advancer disposed on said synchronizer so as to be movable within a predetermined range from the position of said synchronizer, said advancer being capable of stopping at each of said indicated positions when it reaches such position, and means for determining the running mode of the elevator car depending on the position of said advancer relative to the position of said synchronizer when said advancer stops at said indicated position, wherein the improvement comprises a pre-advancer disposed on said advancer so as to be movable with said advancer within a range outside the movable range of said advancer, means for memorizing each said indicated position when said pre-advancer reaches such position, and means for determining the running mode of the elevator car depending on the relation between said memorized position and the position of said synchronizer when said advancer has moved to the limit of its movable range.

3. An elevator control apparatus as claimed in claim 2, wherein means are provided for erasing the memory of all the previously memorized positions when said advancer reaches one of said indicated positions within the movable range thereof.

4. An elevator control apparatus as claimed in claim 1, further comprising a plurality of detecting means disposed on said synchronizer for delivering individual different speed instruction signals to provide a predetermined deceleration pattern, first detected means disposed on said advancer for indicating the floor within a predetermined range out of the floors originating calls, second detected means disposed on the apparatus frame for indicating the remaining floors originating calls, and means for generating a deceleration instruction signal in response to the detection of said second detected means by said detecting means when the elevator car is running at a high speed and in response to the detection of said first detected means by said detecting means when the elevator car is running at a low speed.

5. An elevator control apparatus as claimed in claim 4, wherein said first detected means and those detecting means generating the deceleration instruction signal when the running speed of the elevator car is low are disposed at positions corresponding to the floor positions in said service zone of reduced scale, while said second detected means and those detecting means generating the deceleration instruction signal when the running speed of the elevator car is high are disposed at positions predeterminedly displaced from the floor positions in said service zone of reduced scale.
